UNITED STATES PATENT OFFICE

JOSEPH D. KILLIAN, OF CHEYENNE, WYOMING

OIL VALVE

Application filed June 22, 1928. Serial No. 287,495.

This invention relates to an oil valve used in connection with mechanical forced feed lubricators of locomotives for supplying oil to the valves and cylinders under steam pressure, or while the throttle is shut off and the engine is drifting.

The primary object of the invention is to provide a valve that will automatically open and close after a predetermined quantity of oil has been forced into the body of the valve, the opening and closing of the valve being controlled by the action of oil pressure on a small area of valve head against the minimum and maximum working steam pressure of the locomotive acting on the large area of the valve head, thereby admitting oil to the cylinders.

A further object of the invention is the provision of a valve so constructed that the oil passing therethrough will be thoroughly atomized by the action of the steam to insure the maximum degree of lubrication.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring to the drawings:

Figure 1 is a view illustrating the application of the valve.

Figure 2 is a longitudinal sectional view through the valve.

Figure 3 is a transverse sectional view through the valve, taken on line 3-3 of Fig. 2.

Figure 4 is a transverse sectional view through the valve, taken on line 4-4 of Fig. 2.

Referring to the drawings in detail, the body portion of the valve is indicated generally by the reference character 5 and includes an upper section 6 and a lower section 7, the lower section being provided with a threaded extension 8 to be screwed into a threaded

opening in the steam valve or cylinder to which the valve is applied.

The lower section 7 is formed with a shoulder 9 to receive the valve seat 10 which is formed with an extension 11 defining a guide for the valve stem 12 carrying the valve 13 at its lower end. As clearly shown by Figure 2 of the drawings, the construction of the valve seat and valve is such that a comparatively small upper surface 14 is presented to the oil pressure, which one is admitted to the valve through the upper section of the body portion, while a comparatively large curved surface 15 is presented at the underside of the valve.

An opening 16 is provided in the valve seat 11 and establishes communication between the compartment 17 above the valve, and oil chamber 18 above the valve housing to the end that oil may pass to the upper surface 14 of the valve 13. Positioned on the valve seat and surrounding the extension 11, is a coiled spring 19 that has its upper extremity resting against the flange 20 of the cap 21 which is held to the valve stem 12 by means of the nut 22 whereby the tension of the spring 19 may be regulated to cause the valve to operate under various pressures.

At the upper end of the upper section of the body portion is an opening which is threaded to accommodate the threaded extremity of the pipe 23 that extends from the force feed lubricator, so that oil under pressure will be admitted to the upper section of the valve body, from where it passes to the upper surface of the valve, through the opening 16.

The threaded extension 8 of the valve being formed with a bore 24, it will be obvious that the curved surface 15 of the valve is subjected to the steam pressure in the cylinder or valve on which the device is mounted.

In the operation of the device oil from the force feed lubricator will be admitted to the oil chamber 18 until the pressure of the oil in the oil chamber increases to such a degree as to overcome the steam pressure acting against the surface 15 of the valve, whereupon the valve will be moved from its seat allowing oil to pass into the lower section of

the valve body where it mingles with the steam and is atomized and carried into the valve or cylinder on which the device is mounted, to lubricate the moving parts thereof.

5 If the engine is shut off and allowed to drift, the oil pressure in the oil chamber 18 will act to unseat the valve which is held in a seated position by spring 19, allowing the
10 oil to pass into the lower section of the valve, whereupon the steam passing upwardly will mingle with the oil forcing it against the curved under surface of the valve 13 giving the oil a swirling motion from where it passes
15 to the cylinders or valves in an atomized form.

I claim:

A valve for force feed lubrication, comprising a valve housing, a removable valve seat
20 mounted within the housing and dividing the housing into upper and lower compartments, said valve seat having an extension, a valve member including a valve stem, mounted within the extension, said valve engaging the
25 valve seat to control the passage of oil through the valve, a coiled spring surrounding the extension, a cap on one end of the valve stem and engaged by the spring to normally hold the valve seated, said valve seat
30 having an opening to allow oil to pass therethrough, and inlet and outlet pipes connected with the housing.

In testimony that I claim the foregoing as my own, I have hereto affixed my signature.

JOSEPH D. KILLIAN.
